J. Vickerstaff.

Knit Fabric.

N° 17,612.

Patented Jun 16, 1857.

UNITED STATES PATENT OFFICE.

JOSEPH VICKERSTAFF, OF PHILADELPHIA, PENNSYLVANIA, ASSIGNOR TO MARTIN LANDENBERGER.

KNITTED FABRIC.

Specification of Letters Patent No. 17,612, dated June 16, 1857.

To all whom it may concern:

Be it known that I, JOSEPH VICKERSTAFF, of the city of Philadelphia and State of Pennsylvania, have invented a new and useful Improvement in Knitted Fabrics; and I do hereby declare the following to be a full, clear, and exact description of the same, reference being had to the accompanying drawing and to the letters of reference 10 marked thereon.

My invention relates to improvements in that class of ornamented knitted fabrics in which threads of various colors are used to produce the required pattern, and my improvement consists in knitting simultaneously and in juxtaposition to each other two separate thicknesses and interlocking the same together at any required intervals by transposing the threads for forming the 20 loops of one thickness, so as to form the loop of the other thickness, alternately; thereby producing an ornamental fabric with a variety of differently shaped and differently colored figures on both sides which present a 25 plain uninterrupted surface of loops the latter differing in no respect, at the point of transposition of the threads, from other portions of fabric, and both sides of the fabric being free from the loose unknitted threads 30 common to other knitted fabrics, which are ornamented by the transposing of differently colored threads.

On reference to the drawing which forms a part of this specification Figures 1—2 are 35 diagrams representing the transposition of differently colored threads so as to produce my improved ornamented knitted fabric. Fig. 3 a diagram in perspective representing the result of such transposition.

40 A represents one of a row of threads for knitting one thickness of my improved fabric, and B one of another row of threads for knitting another thickness, the thread A being red and the thread B blue. As seen 45 in Fig. 1 the red thread A is being operated upon by the needle C and the blue thread B by the needle D. Should the needles continue to operate thus without the position of the thread being altered, two separate and 50 distinct fabrics would be produced. By transposing the threads however as seen in Fig. 2, that is causing the red thread A to be operated by the needle D, and the blue thread

B by the needle C, the two thicknesses become interlocked, at the point where the 55 transposition takes place, and if the transposition be continued at intervals as the fabric is being knitted the red and blue thread will appear on and disappear from, both sides of the fabric, as seen in Figs. 2 and 3. 60

If a series of different colored threads (as seen in the perspective view Fig. 3) be used for both thicknesses of the fabric and the transposition of these threads occurs at equal intervals it is evident that a plaid pattern with the colors alternating at equal distances apart, as regards the length of the fabric will be produced, the uniformity or regularity of the changes of colors, as regards the width of the fabric, depending entirely upon the arrangement of and change of colors, and shades of colors in, the two sets of threads.

By using a great variety of different colored threads and transposing the latter at irregular intervals, the most elaborate plaid patterns may be produced. My improved fabric however is not confined to plaid patterns only. Instead of transposing the whole of the threads simultaneously, single 75 threads or any number of threads in each row can be transposed by jacquard or other apparatus so that the threads may be made to appear on, and disappear from, both sides 80 of the fabric at irregular intervals thereby 85 producing an endless variety of irregular figures.

The fabric thus manufactured presents, on both sides, a plain uninterrupted, knitted surface, the loops being uniform throughout, and differing at the point of transposition of the threads, in no respect from the loops, of other portions of the fabric. At the same time the loose unknitted threads, which have hitherto been unavoidable in the manufacture of ornamental knitted fabrics are 90 avoided.

I do not claim exclusively the production of a knitted fabric ornamented by the transposition of threads of different colors, but 95

I claim and desire to secure by Letters Patent as a new article of manufacture and commerce—

A fabric knitted with threads of different colors and composed of two separate thicknesses interlocked, during the process of 105

knitting, at any required intervals, by transposing the threads in such a manner that a knitted fabric may be produced, both sides of which shall present a plain uninterrupted 5 surface of loops and free from the loose unknitted threads common to other ornamental knitted fabrics.

In testimony whereof, I have signed my name to this specification before two subscribing witnesses.

JOSEPH VICKERSTAFF.

Witnesses:

HENRY HOWSON,
WILLIAM E. WALTON.
